UNITED STATES PATENT OFFICE.

MICHAEL B. HOLSTEIN, OF RICHLAND, PENNSYLVANIA.

PUMP.

1,330,266.

Specification of Letters Patent. Patented Feb. 10, 1920.

Application filed May 6, 1919. Serial No. 295,189.

To all whom it may concern:

Be it known that I, MICHAEL B. HOLSTEIN, a citizen of the United States, residing at Richland, in the county of Lebanon 5 and State of Pennsylvania, have invented certain new and useful Improvements in Pumps; and I do hereby declare the following to be a full, clear, and exact description of the invention, such as will enable others 10 skilled in the art to which it appertains to make and use the same.

This invention relates to pumps and contemplates more especially an improved multi-barrel air-compressing pump for inflating pneumatic tires.

An object of the present invention is the production of a compound pump in which a maximum quantity of air is progressively compressed and finally discharged into the 20 article to be inflated by a direct downward movement of one of the pistons.

Another object of the invention is to produce a compound pump comprising a series of concentric barrels the innermost two of 25 which are relatively closely spaced from each other for purposes of readily conveying the air from the outer or low pressure cylinder to the inner or high pressure cylinder in such a manner as to assist the operation in an upward stroke of the pump, and to admit partially compressed air into the high pressure cylinder whereby on the downward stroke of the pump the air is further compressed and discharged directly 30 into the article being inflated.

A further object of the invention resides in the production of a simple, durable and efficient pump which can be easily assembled and disassembled, and in which the 40 best quality of relatively flexible and tough packing material or cups may be utilized with a minimum amount of depreciation or wear.

With these and other objects in view, the 45 invention further consists in the combination and arrangement of the several parts including an adjustable handle which can be readily secured to the outer barrel at different heights whereby a full stroke and 50 consequent maximum efficiency is always obtainable with the expenditure of the least possible effort.

In the accompanying drawings illustrating an embodiment of my invention, and

in which similar reference characters designate corresponding parts,

Figure 1 is a perspective view of my improved pump, and

Fig. 2 is an enlarged vertical sectional view.

The present invention has been primarily designed for use in connection with inflating automobile tires. Heretofore attempts have been made to produce a commercially successful pump in which air would be progressively compressed and easily discharged into the tire. Certain difficulties have, however, been experienced. Those in particular have been non-durability of the packing, because of the direct wear thereof on the 65 stem or piston rod of the high pressure piston; an excessive manual strain upon the operator in supplying and compressing a sufficient amount of air; and complexity of construction tending to make the repair 70 of the pump a most tedious task as well as a comparatively expensive one.

The present invention overcomes these difficulties, and comprises among other things, an outer low pressure cylinder 80 formed by a relatively large movable barrel; a stationary piston member for said cylinder; an inner high pressure cylinder formed of a relatively small stationary barrel; a piston for said high pressure cylinder connected to and movable with the barrel of the low pressure cylinder; and means including a novel form of concentric air conduit or passageway, for conveying the air 85 from the low to the high pressure cylinder. 90

Referring to the drawings, the pump is shown as particularly adapted for foot and hand use, although it will be understood that other applications of the principles of the invention may be resorted to without 95 departing from the spirit thereof, and I do not limit myself to the exact disclosure set forth herein. The pump 1 is supported upon a base 2, and is provided with a flexible tube 3, for attachment to the valve of a tire, as will be readily understood. The handle 4 is adjustably secured to the pump and being of novel construction will hereinafter be described in detail.

The low pressure cylinder 5 is formed between an outer movable barrel 6, and an inner stationary barrel 7. The stationary barrel 7 is suitably secured or shrunk over

a base plug 8 provided with an interlocking shoulder 9 and screwed into the base or support 2, as shown. The shoulder 9 rests upon an upstanding boss 10 formed integral with the base 2, and serves to form a rigid yet easily detachable connection. The base plug 8 is slightly tapered as at 11, the upper end of the said tapered portion 11 terminating in a shoulder and reduced portion 12 of the 10 plug upon and against which the stationary barrel 7 is brazed or otherwise secured. An opening 13 is formed through the plug 8, and serves to conduct the compressed air from the pump to a chamber 14 in the base 2, from whence it passes into the tube 3 without interruption by valves or other check devices.

The stationary piston 15 which coöperates with the movable barrel 6 of the low pressure cylinder is threaded as at 16 upon the upper end of the stationary barrel 7. The piston 15 comprises a flanged member 17 upon which a cup packing 18 is held in place by a nut 19, as shown. The cup packing 18 is of a durable and yielding character, and is arranged so that its lower flange 20 extends downwardly, as shown. It will be seen that upon the down stroke of the barrel 6 the flange 20 of the packing will yield 25 sufficiently to allow air to enter openings 21 in the cap 22 and pass into the low pressure cylinder. Upon the up stroke, the flange 20 of the packing will be forced against the inner wall of the barrel 6 and permit of its 30 being compressed as will be presently described.

The upper end of the stationary barrel 7 is provided with a flange 23 which abuts against the flanged member 17, as shown, 40 and is further formed with an internally threaded portion 24 into which the upper end of the barrel 25 of the high pressure cylinder is secured.

The barrel 25 of the high pressure cylinder is slightly spaced from the inner barrel 7 of the low pressure cylinder, thereby producing a concentric air conduit or passageway 26 extending throughout the length of the pump and for a purpose to be presently described. Brazed or otherwise secured to the lower end of the barrel 25 of the high pressure cylinder is a fixed head member 27 having a threaded portion 28. A cup packing 29 is positioned against this head 27 and 50 has a depending flange 30, as shown. The flange 30 is of yielding material and is designed to terminate short of the upper end of the base plug 8, as shown. A nut and washer 31 serves to secure the packing 29 55 in position.

In operation, the flange 30 of the packing yields sufficiently to permit the passage of the air as it is compressed by the up stroke of the barrel 6 and forced from the low pressure cylinder through opening 32 down-

wardly through the concentric passageway 26. Upon the downstroke of the piston of the high pressure cylinder the flange 30 is forced against the inner wall of its stationary barrel 7 as will be understood. 70

An opening 33 extends through the head member 27 and establishes communication between the intermediate chamber 34 and the high pressure cylinder.

The piston 35 of the high pressure cylinder is formed of a head member 36 secured upon a shouldered end of a stem or piston rod 37. This shouldered end is screw threaded as at 38 and receives a nut 39 between which and the head 36 a cup or other 80 packing 40 is positioned. In practice, the packing 40 may be of relatively hard or stiff material capable of long usage and need not be as yielding in quality as those heretofore described. This will be apparent, for 85 there is but one function of the high pressure piston, and that is to further compress the initially compressed air and force same through the tube 3 into the tire being inflated. 90

The piston rod 37 extends upwardly through the high pressure cylinder, and is secured to the cap 22 by shrinking, brazing, or in any other suitable manner. By this construction it will be seen that the high 95 pressure piston and outer barrel 6 of the low pressure cylinder move together. It will also be noted that the usual packing or stuffing box through which the piston rod of the high pressure piston has heretofore 100 usually passed, is eliminated, and a direct thrust made possible for discharging the progressively compressed air, in an easy manner and without the usual frictional resistance due to the packing of the piston rod. 105

A spring member 41 is shown as interposed between the cap 22 and the flanged end 23 of the stationary barrel 7. This spring serves to arrest and absorb the downward thrust of the pump, as will be understood. It is perforated at 41' to permit of the piston rod passing freely therethrough. While I have shown this form of cushioning device, it will be understood that other types may be readily inserted. 115

The movable barrel 6 of the low pressure cylinder is provided at its lower end with a detachable head section 42, as clearly shown in Fig. 2. This head section 42 moves with the barrel 6 and slides upon the stationary barrel 7. It comprises a packing 43 designed to prevent the escape of air from the low pressure cylinder, and a ring member 44 suitably secured to the barrel 6, as by thread 45. The member 44 is provided with an upstanding flange 47 between which and the barrel 7 the packing 43 is positioned. 120

Another member 48 having a downwardly extending guiding sleeve 49 is 125 130

threaded into the aforesaid member 44 and serves to clamp the packing 43, as shown. By this construction it will be seen that this head section 42 can be easily removed, whereby, together with the removal of the cap 22, the pump can be further and completely disassembled.

The handle 4 is shown as comprising a circular clamping portion 47' from which 10 extend hand gripping sections. Bolts 48' extend through ears 49' formed on said circular portion and serve to securely attach the handle to the barrel 6 in an adjusted position. The hand gripping sections are 15 preferably uniform in diameter, and are arranged diametrically opposite as shown. From this construction it will be seen that for persons of varying heights the adjustment of the handle 4 will conveniently permit of a full stroke with a minimum expenditure of effort.

The operation follows:

An operator grasps the handle 4 and moves the outer barrel 6 upwardly, giving 25 to the pump what is termed an upstroke. In imparting a downward movement or down stroke to the barrel 6, air is drawn in through the openings 21 in the cap 22. This air passes the flange 20 of the cup packing 30 18 and fills the low pressure cylinder 5. Upon the succeeding upstroke this air is gradually compressed and forced through the openings 32 in the stationary barrel 7, into the concentric conduit or passageway 35 26, from where it passes downwardly, forcing its way past the yielding flange 30 of the cup packing 29 and into the chamber 34. From this chamber it first begins to 40 pass into the article being inflated up to a pressure of approximately twenty pounds, more or less, after which the partially compressed air passes upwardly through the opening 33 into the high pressure cylinder. The effect of this partially compressed air 45 entering the high pressure cylinder beneath the piston 35 is to assist the upward movement of said piston as will be understood.

Upon the succeeding downstroke of the pump the high pressure piston 35 will further compress the air and force it directly through openings 33 and 13 into the chamber 14 and thence into the tube 3 by which it is conducted to the tire or other object being inflated.

55 It will be seen from the foregoing that upon the down stroke of the pump, air is initially drawn into the pump and at the same time the heretofore progressively compressed air is discharged from the pump 60 through the tube 3. Upon the upstroke of the pump the air is partially compressed, and directed into the high pressure cylinder beneath the piston therein for purposes of assisting the upward movement of same. 65 This course of the air occurs, it will be

noted, after the discharge of the initially compressed air has passed through the chamber 34 up to a pressure of about twenty pounds, more or less, in the double acting operation of the pump, as will be understood.

70 From the foregoing it will be obvious that an efficient and easily operated hand pump has been produced, wherein advantage of extreme longevity of use has been 75 made possible, together with a constructional arrangement for purposes of repair heretofore unknown.

I claim:

1. A pump of the class described comprising a low pressure cylinder formed of relatively movable and stationary barrels, a piston for said low pressure cylinder carried by the stationary barrel, a high pressure cylinder consisting of a stationary barrel 85 closely spaced from the stationary barrel of the low pressure cylinder, a piston for said high pressure cylinder connected to and movable with the movable barrel of the low pressure cylinder, and means including the passageway formed between the aforesaid closely spaced stationary barrels for conducting the compressed air from the low to the high pressure cylinder.

90 2. A pump of the class described comprising a low pressure cylinder formed of relatively movable and stationary barrels, a piston for said low pressure cylinder carried by the stationary barrel, a high pressure cylinder consisting of a stationary barrel located 100 within and closely spaced from the aforesaid stationary barrel of the low pressure cylinder, a piston for said high pressure cylinder connected to and movable with the movable barrel of the low pressure cylinder, and means including a flexible packing located 105 in the passageway formed between the aforesaid closely spaced barrels for admitting the partially compressed air to the high pressure cylinder beneath the piston therein.

110 3. A pump of the class described comprising an outer movable barrel and an inner stationary barrel forming a low pressure cylinder, a stationary piston for said low pressure cylinder, another stationary barrel 115 located within and closely spaced from the aforesaid stationary barrel forming a high pressure cylinder, a movable piston for said high pressure cylinder connected to and movable with the movable barrel of the low pressure cylinder, and means for admitting the partially compressed air between the aforesaid closely spaced stationary barrels to the high pressure cylinder beneath the piston therein.

120 4. A pump of the class described comprising an outer movable barrel and an inner stationary barrel forming a low pressure cylinder, a stationary piston therefor including a flexible packing around which air is 130

initially drawn into the pump, another stationary barrel closely spaced from the aforesaid stationary barrel forming a high pressure cylinder, a movable piston therefor, and a flexible packing located in the passageway formed between the closely spaced barrels whereby air is partially compressed and conducted from the low pressure cylinder to the high pressure cylinder beneath the movable piston therein on the up stroke of the pump, and further compressed and discharged from the pump on the down stroke thereof.

5. A pump of the class described comprising an outer movable barrel and an inner stationary barrel having an opening therein at its upper end, a stationary piston provided with a flexible packing and located within said barrels, another stationary barrel located within and closely spaced from the aforesaid stationary barrel, a movable piston therefor interconnected and movable with the outer movable barrel, and a flexible packing located in the passageway formed between the closely spaced barrels at their lower ends

whereby air is partially compressed by the upward movement of the outer barrel and conducted downwardly through the aforesaid passageway into the second mentioned stationary barrel beneath the piston therein.

6. A pump of the class described comprising a supporting base, a barrel secured to said base, a second barrel secured to the aforesaid barrel, a movable barrel encircling the first mentioned barrel, a cap for said movable barrel, a piston rod secured to said cap and provided at its lower end with a piston operable within the second mentioned barrel, a spring member interposed between said cap and the upper end of the barrel secured to the supporting base, and a handle secured to said outer barrel for operating the pump.
